United States Patent Office

Des. 187,161
Patented Feb. 2, 1960

187,161

WASTE RECEPTACLE OR SIMILAR ARTICLE

Charles O. Bliss, Los Angeles, Calif.

Application April 14, 1958, Serial No. 50,449

Term of patent 14 years

(Cl. D58—4)

FIG. 1

FIG. 3

FIG. 2

Fig. 1 is a top plan view of a waste receptacle or similar article showing my new design;

Fig. 2 is a side elevation thereof;

Fig. 3 is a cross-sectional view thereof taken on the line 3—3 of Fig. 2 on an enlarged scale.

I claim:

The ornamental design for a waste receptacle or similar article, substantially as shown.
